UNITED STATES PATENT OFFICE

GEORGE W. SCHAEFER, OF SOUTH BRAINTREE, MASSACHUSETTS, ASSIGNOR TO ADDRESSOGRAPH COMPANY, OF CHICAGO, ILLINOIS, A CORPORATION OF DELAWARE

INDEX TAB

Original application filed October 1, 1925, Serial No. 59,825. Divided and this application filed May 8, 1928. Serial No. 276,053.

This application is a division of my application Serial No. 59,825, filed October 1, 1925.

This invention relates to printing devices having a printing form and which are adapted to be stored in accordance with a card index system or in a stack and to be run through an addressing or other suitable machine for taking impressions from the form.

10 The object of the invention is to provide a novel tab or card holder which is adapted to be slidably engaged with the printing device at the top thereof so that it can be easily adjusted between the ends of the device and used for indexing or classifying purposes.

The invention is capable of use with many different kinds of printing devices and, for the purpose of this application, I have shown it applied to a printing device of that class 20 which comprises a frame carrying a detachable plate and a detachable card and, referring to the drawings

Fig. 1 is a front elevation of a printing device with my improved tab applied thereto.

25 Fig. 2 is a sectional view on the line 2—2 of Fig. 1.

Fig. 3 is an enlarged view of the tab and a portion of a printing device frame.

Fig. 4 is a perspective view of the tab. 30 The printing device illustrated comprises a frame 5, a printing plate 6 and a card 7, the frame having suitable retaining devices for detachably holding the plate and the card thereon. The plate has printing characters embossed thereon. The upper edge of the frame is provided with a bead 8.

The tab shown is made in the form of a holder comprising a plate 9, having a flange 10 at the top and flanges 11 at the ends to 40 receive a card 12 bearing indexing or classifying data. Two legs 13 project downwardly from the lower edge of the plate 9 and adjacent the plate these legs are bent forward to form forwardly projecting portions 14. Each leg is bent reversely upon itself below said portions 14 to form a recess 15 to receive the edge of the bead 8 and a rib 16 to fit in the bead. When the tab is applied to the frame the legs will interlockingly engage the bead at the top edge of the

frame and the shoulders at the under side of the bent portions 14 of the legs will engage the top portion of the bead and the tab is thus held against displacement on the frame except that it is capable of being slidably adjusted on the bead between the ends of the frame. The upper sides of bent portions 14 also form shoulders to support the card 12 which rests thereon and is held in place by the flanges 10—11. The tab may be readily engaged with the frame by an endwise movement of the tab relative to the frame to interengage the bead and the reversely bent portions of the legs, and the tab can be readily disengaged from the frame by moving the tab endwise relative to the frame. The tab is preferably made of light spring-metal which will permit it to be shaped for snug engagement with the frame and to yield sufficiently for ready engagement with and disengagement from the frame. I have shown the tab adapted to receive a removable card 12, but it is apparent that the card may be affixed to the tab, or the indexing or classifying data may be printed or otherwise applied directly upon the tab in ways familiar with tabs heretofore used in connection with printing devices of the kind to which my invention is adaptable.

The legs extend below the bent portions and lie flat against the frame behind the card 7. There is sufficient frictional contact between the tab and the frame to hold the tab in adjusted position. The retaining devices 17 may be of the usual form struck up from the frame as shown to hold the card 7 on the frame, but provision may be made to permit the card 7 to project up into the ribs 16 between the folds of the legs forming said ribs so that the legs will also function as retaining devices for the card.

The tab is simple in construction and it is adapted to be easily applied to a frame and to be adjusted between the ends of the frame to any desired position for indexing or classifying purposes. This tab may be used alone or in conjunction with other tabs usually applied to printing devices, and it may be

made in any desired size or shape to meet different conditions.

I am aware that changes in the form, construction and arrangement of parts may be made to adapt the tab for different printing devices and for different purposes, and I reserve the right to make all such changes as fall within the scope of the following claims.

I claim:

- 10 1. A tab for printing devices, comprising a plate adapted to be positioned above the edge of the printing device and in substantially the plane thereof, and an integral leg projecting downwardly from the plate along the face of the printing device, said leg being bent adjacent the plate to form a shoulder, and a rib with a recess therebetween for engagement with a printing device.
- 20 2. A tab for printing devices comprising a plate and a leg, said leg being bent to form a shoulder at the front thereof and adjacent the lower edge of the plate, and a rib back of said shoulder with a recess between the shoulder and the rib to permit engagement 25 of the tab with a printing device.
- 30 3. A tab for printing devices comprising a plate having devices thereon for retaining a card, and a leg projecting downward from the plate, said leg being bent adjacent the plate to form a shoulder to receive the lower edge of the card, and said leg being also bent adjacent said shoulder to form a rib with a recess therebetween to permit engagement 35 of the tab with a printing device.
- 40 4. The combination of a printing device having an integral recessed bead at one edge, and a tab comprising an elongated leg extending downwardly over the face of the printing device and bent intermediately to 45 slidably interengage with said bead.
- 45 5. The combination of a printing device having a recessed bead at its upper edge, and a tab comprising a plate and a leg, said leg being bent to form a rib to engage the recess in the bead and a shoulder spaced from the rib to form a recess for receiving the edge of the bead.
- 50 6. The combination of a printing device having a bead at one edge, and a tab comprising a card-holding plate and a leg, said leg being bent to form an upper shoulder for supporting the card on said plate at the front of the plate, a lower shoulder, and a rib, said rib being spaced from the lower shoulder 55 to form a recess to slidably engage said bead.
- 60 7. The combination of a printing device having a bead at one edge, and a tab comprising a plate, retaining devices on the plate for holding a card, and a leg projecting from the plate, said leg being bent to form an upper shoulder at the front thereof and adjacent the plate to support the card, a lower shoulder and said leg being also bent to form 65 a rib separated from said shoulder by a recess

to interlockingly engage the bead for slidably mounting the tab on the frame.

8. The combination of a printing device frame having card retaining devices thereon and a bead at its upper edge, a card engaged with said retaining devices, and a tab comprising a plate and an elongated depending leg, said leg being positioned between the frame and the card and being bent at its upper end to slidably engage said bead on the front thereof.

GEORGE W. SCHAEFER.
